BOTTLE CAP

Yue San Fong, Hong Kong, China

Application January 24, 1950, Serial No. 140,184

1 Claim. (Cl. 215—46)

1

This invention relates to bottle caps, and more particularly to resilient, removable bottle caps of a type which can be applied to or removed from the top of a bottle over and over again.

A main object of the invention is to provide a novel and improved bottle cap of the type which may be applied to and removed from the neck or spout of a bottle repeatedly, as desired, the cap being very simple in construction, being easy to manipulate, and providing a tight seal.

A further object of the invention is to provide an improved resilient, spring locking bottle cap which is very inexpensive to manufacture, which involves only a few parts, and which may be applied and removed by very simple manual operations.

Further objects and advantages of the invention will become apparent from the following description and claim, and from the accompanying drawings, wherein:

Figure 1 is a top view of an improved bottle cap constructed in accordance with the present invention;

Figure 2 is a vertical cross-sectional view taken on line 2—2 of Figure 1, showing the bottle cap mounted on the top of a bottle;

Figure 3 is a side elevational view of the bottle cap of Figures 1 and 2 shown mounted on a bottle;

Figure 4 is an enlarged cross-sectional detail view taken on line 4—4 of Figure 3;

Figure 5 is a bottom plan view of the bottle cap of Figures 1 to 4.

Referring to the drawings, the improved bottle cap comprises a main, resilient sealing body 11 which is circular in shape and which is formed of rubber or other suitable deformable elastic material. The sealing member 11 is molded with an outer depending annular flange 12 and an inner depending annular flange 13 which is substantially longer and thicker than the outer flange 12, and which is adapted to be sealingly fitted into the neck of a bottle, such as the bottle 14 shown in Figures 2 and 3. Designated at 15 is a resilient, flat, metal cover member which extends across the main sealing member 11 and which is formed with depending flanges 16 and 17 which are engaged over the outer annular flange 12 of the sealing member 11, the depending flanges being inwardly turned at 18 and 19 to define gripping fingers adapted to engage lockingly with the top bead, indicated at 25, of the bottle 14. Interposed between the flange 17 and the flange 12, as shown in Figure 2, is a depending lever 20, said lever being formed at its in-

2

termediate portion with horizontal notches 21, 21 which receive the marginal portions of a notch 22 formed at the intermediate portion of the in-turned flange element 19. The horizontal notches 21, 21 on the lever 20 and the notch 22 on the inturned end 19 of the flange 17 of the cover member 15 constitute interengaging means for connecting the lever 20 to the flange 17 of the cover member 15.

10 In using the bottle cap, the cap is placed on top of the bottle and pressure is applied to the central portion of the cover member 15, causing said central portion to flex downwardly and allowing the flanges 16 and 17 to be slipped over 15 the top bead of the bottle, the inner flange 13 of the sealing member 11 being meanwhile pushed into the bottle opening. When the resilient cover 15 is released, it restores itself to its normal configuration, wherein the flanges 18 and 19 lockingly engage beneath the top bead 19 of the bottle in the manner shown in Figure 2, the bottle opening being sealed by the engagement over the rim thereof of the elastic sealing member 11. If the bottle contains gas under pressure, as in the 25 case of carbonated beverages, the gas pressure exerts an upward force on the central portion of the cap, causing the cover member 15 to be bowed upwardly and increasing the gripping action of the flange elements 18 and 19. To remove the 30 cap it is merely necessary to grasp the lower end of the lever 20 and exert an upward and outward force thereon, thereby separating the flange 17 from the bead 25, whereby the bottle cap may be lifted off the top of the bottle.

35 It is obvious that the bottle cap above described may be employed over and over again, and that by the use thereof a bottle may be sealed in a gas tight manner, whereby beverages in the bottle will not suffer any deterioration or loss of flavor. 40 While a specific embodiment of an improved removable and replaceable bottle cap has been disclosed in the foregoing description, it will be understood that various modifications within the spirit of the invention may occur to those skilled 45 in the art. Therefore, it is intended that no limitations be placed on the invention except as defined by the scope of the appended claim.

What is claimed is:

50 A bottle cap comprising a generally circular sealing member formed of elastic deformable material, an outer depending annular flange carried by said sealing member, an inner depending annular flange carried by said sealing member, a cover member of thin resilient metal extending 55 across the top of said sealing member, depending

inturned flanges at the respective ends of said cover member, and a depending lever disposed between the outer depending annular flange of the sealing member and one of the depending flanges of the cover member, said one of the cover member depending flanges being notched at its inturned portion and the lever fitting in the notch and being notched at its sides to interfit with the margins of the notch of said inturned portion.
